OUTBOARD MOTOR GUARD

Theodore Francis Crew, Baltimore, Md.

Application March 24, 1954, Serial No. 418,410

3 Claims. (Cl. 115—42)

This invention is a motor guard adapted particularly for use in connection with outboard motors, having for its primary object to provide means for completely housing the propeller and drive mechanism of the motor to prevent the loss or injury of the hands, arms, legs or other parts of the body of those who may accidentally come in contact therewith during the operation of the motor.

A further object of the invention is to provide a guard to protect the propeller and steering fin of the motor against damage by contacting the ground in shallow water, submerged obstructions in the water, and against the access to the propeller or steering fin of weeds, grass or other plants or material which likely would foul or damage the same.

A further object of the invention is to provide a guard of the character thus generally defined which is of light weight, of simple construction, which may be applied to boats of various sizes and types without the exercise of special skill and without the necessity for special tools or appliances.

A further object of the invention is to provide a guard which, of light weight and simple construction, possesses sufficient rigidity to prevent the same from serious damage or collapse in the event it should contact some obstruction in the travel of the boat; the cage or housing being so constructed and shaped as to readily pass over any obstruction without damage to the guard itself.

A further and particular object of the invention is to provide a guard of the character generally stated which provides means whereby the motor may be easily applied to or removed from the guard without disturbing the latter, the parts affording these operations being so constructed as to be readily operated for either insertion or removal of the lower part of the outboard motor and which, when the motor is properly positioned, maintains the housing in entirely closed position to prevent access thereto of foreign matter such as grass, roots, etc., usually encountered in marine activities.

With the foregoing objects in view, together with others which will appear as the description proceeds, the invention resides in the novel construction, combination and arrangement of parts, all as will be described more fully hereinafter, illustrated in the drawing, and particularly pointed out in the claims.

In the drawing:

Fig. 1 is a fragmentary side elevation of the rear or stern portion of a conventional type of row boat and illustrating as applied thereto a guard constructed in accordance with the invention.

Fig. 2 is a top plan view of the guard removed from the boat.

Fig. 3 is a sectional view taken through the housing substantially on line 3—3 of Fig. 1, and

Fig. 4 is a fragmentary top plan view, on a slightly enlarged scale, illustrating a modified form of the invention.

Referring now more particularly to the drawing, the boat, represented generally at 5, is provided with the usual plate or stern piece 6 and skeg 7.

It will be understood that the guard of my invention may be used in connection with any of the well known types of outboard motors now in use. In the present instance, the motor includes the depending shaft housing 8 at the lower end of which the propeller 9 is mounted to be driven by suitable shaft and gearing, not shown, contained within the housing, as will be understood.

2

The entire motor structure is mounted, as usual, in vertical position midway the sides of the boat 5 and is held in clamped position thereon by the clamping member indicated at 10. It will be understood that steering operations are carried out through the instrumentality of the lever or tiller indicated at 11.

The housing of my invention includes a bracket formed of light angle iron and indicated generally at 12 secured adequately to the plate 6 of the boat. This bracket constitutes the forward end of the guard and provides spaced parallel arm portions 13 of angle construction through which screws or other fastening elements 14 are passed to secure the bracket firmly to the plate 6 of the boat. The intermediate bracket arms 13 are connected at their lower ends as at 15 to provide a drop section to accommodate the skeg 7 of the boat.

The outer arms 13 have connected thereto the rearwardly extending parallel frame members 16 which extend upwardly at their rear ends and then forwardly to provide top frame members 17 connecting with the upper ends of the bracket arms 13. The sides and rear of the frame thus constructed may have secured thereto spaced panel members 18 to lend rigidity to the structure, and the sides, bottom, and rear of the frame is covered with open mesh fabric of wire or other durable material 19 to preclude the entry of grass, leaves, brush or other material to the interior of the cage thus formed.

It will be noted, particularly with reference to Fig. 1 of the drawing, that the side frame members 16 incline in an upward direction from the rear end of the frame proper to the bracket arms 13 so as to provide, in effect, upwardly inclined runners to enable the boat to ride easily upon the bottom of a stream when shallow water is encountered, or to "ease" the boat over obstructions such as logs, roots or other sizeable obstructions which might be encountered as the boat advances.

The top of the frame thus described is provided with a plurality of doors or gates indicated generally at 20. These gates are hinged to the frame per se as at 21, and are capable of being swung upwardly in opposite directions to open position to permit of application of the housing 8 and the propeller to the interior of the frame. When the motor is properly applied, the gates are swung together in lowered position, and the gates are cut away at their adjacent edges as at 22 to conform generally to the shape of the propeller shaft housing 8 but permit sufficient clearance therefrom to allow the necessary rotative movement of the shaft housing in steering operations. In one form of the invention, the gates 20 are held in closed position by latches indicated at 23.

In Fig. 4 of the drawing, a slight modification is illustrated, wherein the gates 20 are supported by spring hinges indicated at 24; the springs of these hinges tending normally to force the gates into downward or closed position.

In practice, the frame is attached at its forward end to the stern of the boat by passing the securing rivets or bolts 14 through the forward bracket arms into the plate 6. When it is desired to apply the motor to the boat, the gates 20 are swung to open position permitting the propeller and steering fin to freely enter the frame and to descend therein the proper distance. The gates 20 are then swung to closed position and latched as shown in Fig. 2 or maintained in closed position by the spring hinges 24 as shown in Fig. 4. The propeller and such other parts of the outboard motor as will be immersed will thus be entirely enclosed by the mesh frame and the access to the interior thereof of damaging foreign matter will be precluded. The entire frame and its associated parts may be made of light yet strong metal to adequately protect the motor against damage or the propeller becoming fouled. The protective frame or guard constructed in accordance with my invention may be manufactured at low cost, may be readily applied to or removed from the boat without special skill or tools, and yet will prove adequate in carrying out the several objects set forth.

I claim:

1. A propeller guard for boats comprising a hollow frame, arm portions on said frame at the forward end thereof to be secured to and conforming with the stern

3

of said boat, the said frame projecting beyond the said stern and open at its upper end, gate sections pivoted in spaced parallelism to the edges of said frame portion defining said opening, means for securing said gate sections in closed position, and mesh fabric covering said frame.

2. A propeller guard for boats comprising a frame having spaced parallel side portions, arm portions at the forward ends of said side portions and projecting forwardly of said frame to be secured to the stern of a boat, a second pair of arm portions disposed inwardly of the sides of said frame and connected together at their lower ends, mesh fabric covering said frame and extending between said arm portions, and gates closing the top of said frame.

3. A propeller guard for boats comprising a frame having spaced parallel side portions, mesh fabric cover-

ing the bottom, front, sides and back of said frame, gates of mesh fabric hingedly connected to the top portions of said side members and normally closing the top of said frame, and said gate members cut away at their adjacent edges to provide between them at a substantially elongated opening.
